UNITED STATES PATENT OFFICE.

HUBERT CREHAN, OF PITTSBURGH, PENNSYLVANIA.

NUT-TAPPING MACHINE.

1,149,553.

Specification of Letters Patent. Patented Aug. 10, 1915.

Application filed May 27, 1914. Serial No. 841,247.

To all whom it may concern:

Be it known that I, HUBERT CREHAN, of Pittsburgh, in the county of Allegheny and State of Pennsylvania, have invented a new and useful Improvement in Nut-Tapping Machines, of which the following is a full, clear, and exact description, reference being had to the accompanying drawings, in which—

10 Figure 1 is a plan view of my improved apparatus; Fig. 2 is a side elevation; Fig. 3 is an end elevation, the hopper being removed; Fig. 4 is a view partly in section, showing the reversing screw; Fig. 5 is a 15 like view showing the lead screw; Fig. 6 is an enlarged view of the tapping chuck in operative position for tapping the nut; Fig. 7 is a sectional view of the tap chuck; Fig. 8 is a sectional view of the tap chuck, 20 the parts being in the position assumed when the tap meets an obstruction; Fig. 9 is an end view of the nut feeding mechanism; Fig. 10 is a side elevation of the nut feeding mechanism; Fig. 11 is a horizontal 25 sectional view of the hopper and portion of the feed mechanism on the line 11—11 of Fig. 9; Fig. 12 is a vertical sectional view on the line 12—12 of Fig. 11; Fig. 13 is a detached elevation of one of the feeding 30 arms; Fig. 14 is a plan view of the same; Fig. 15 is a vertical sectional view on the line 15—15 of Fig. 13; Fig. 16 is a detached 35 end elevation of the block which closes the end of the openings in the hopper in which the feeding arm acts; and Fig. 17 is a detached side elevation of the same.

My invention relates to that class of apparatus for automatically tapping or threading nuts in which the nuts are fed continuously and automatically from a hopper to a matrix where they are successively subjected to the action of a reciprocating and rotary tap, and it consists in mechanism for operating and automatically reversing the movement of the tap and for feeding the blanks to and releasing the threaded nut from the matrix; it also consists in mechanism by means of which power is applied to a series of taps from a common source, 45 in safety devices to prevent the clogging and breaking of the operative parts, and in mechanism embodied in the several parts as is hereinafter more fully described.

In the drawing 2 represents the central 50 power shaft supported by the housings 3 which may be mounted or fixed to any suit-

able bed plate. Keyed to the shaft 2 is the band wheel 4, on each side of which and loosely mounted on the shaft 2 are the band wheels 5, 5. Embracing these band wheels are two belts, one of which is crossed, which belts pass over band wheels on a power shaft, which, as well as the belts, are not shown in the drawing. Mounted on the bed plate are two standards 28 in the upper portions of which are slots through which passes the sliding bar 25; the bar resting on anti-friction wheels 29. Keyed to the sliding bar 25 are two belt guides 26 having slots through which pass the belts that drive the wheel 4. By means of these belt guides the two belts may be shifted from either of the loose band wheels 5 to the keyed band wheel 4 by the movement of the bar 25, which movement is produced by the lever 22 at the upper end of which is a weight 23 and in which is a slot and pin connection 24 which connects the lever 22 with the bar 25. This lever 22 is keyed at its lower end to the rock shaft 22'. The movement of the bar 25 is limited by the stops 27, 27, which come in contact with the standards 28.

Keyed to the shaft 2 is a wide gear wheel 6 which meshes with the gear wheels 7, 7 which are keyed to the shafts 8, 8. Mounted on the shafts 8 are threaded sleeves 9 which are secured to the shafts 8 by the pins 10. The shafts 8 are mounted in the bearings 8², 8² and threaded bearing 9' which is fitted in the standard 8', the thread of which engages with the screw of the sleeve 9. At each end of the shafts 8 are tap carrying chucks 11. Keyed to one of the shafts 8 is the wide gear wheel 14 which meshes with a gear wheel 15 which is keyed to one end 95 of a reversing screw 16 constituting a reversing shaft, the thread of which engages with the interior threads of the blocks 17, 17 which are slidably mounted on the slide bar 17' and on which the blocks 17 are 100 caused to travel by the rotation of the screw 16. This bar 17' is detachably connected to the standards 8', 8² by means of the screw 31 in the top 16' of the standard 8'. The purpose of this is to allow the bar 17' to 105 be withdrawn from the standards and the blocks 17, after which the blocks 17 may be turned on the thread 16 to bring them closer together or farther apart and thus shorten or lengthen the reversing movement 110 of the apparatus. Between the blocks 17, 17 is the rocking lever 18 which is keyed to the

shaft 19 at the other end of which is keyed a lever 20 to which is pivoted one end of the arm 21, the other end being pivoted to a lever arm which is keyed to the shaft 22'. By the rotation of the reversing shaft 16 one of the sliding blocks 17 comes in contact with the lever arm 18 and throws it over, thus giving a partial rotation to the shaft 19 which in turn moves the levers 20, 21, arm 22, and bar 25, thus shifting the belt guides 26, 26 on the band wheels 5, 4 and 5, this movement being assisted by the weight 23 at the end of the arm 22, whereby the movement of the main power shaft 2 is reversed. The rotation of the shaft 8 and threaded sleeve 9 causes the shaft 8 to move longitudinally; first forwardly to carry the tap 12 through the cavity in the nut and then, as the mechanism is reversed as just described, backwardly to withdraw the tap.

The chuck 11 which carries the tapping bit 12 in the removable bushing 37 is in the form of a sleeve which fits on the ends of the shafts 8 and is secured thereon by means of the pin 32 fitting in the slot 32' and also by the lugs 33 having inclined end faces which seat in the V-shaped cavities 34 in the shaft 8, the lugs 33 being normally held in position by the leaf springs 35. The purpose of this connection between the chuck 11 and the shaft 8 is to permit the chuck 11 to slide backwardly on the shaft should the bit 12 encounter an obstruction, the excessive pressure of which on the bit being exerted on the chuck causes the lugs 33 to slip out of the cavities 34, allowing the chuck to slide back on the shaft 8, the pin 32 moving in the slot 32'. The leaf springs 35 are secured to the chuck 11 by means of the bolts 38, and the springs are held in position by the pins 36 fitted in cavities formed in the chuck. The purpose of the gear wheels 6 and 14 being wide is to permit of the reciprocatory movement of the gear wheels 7 and 14, which are keyed to the shaft 8, without losing mesh with the gear wheels 15 and 6. Owing to this arrangement of a central power shaft with two tapping shafts, it is possible to place four taps on one bed plate; one at each end of the two shafts 8, which are arranged on both sides of the central shaft 2; the only difference between the mechanism on one side from that on the other being that on one is the reversing mechanism which reverses the movement of the shaft 2, which mechanism is not duplicated on the other side of the apparatus.

The nut feeding mechanism is composed of a hopper, feeding arms and actuating mechanism, and a chute which leads from the hopper to the matrix in which the nuts are tapped. In the drawings 60 represents the hopper, which is secured to the vertical plate 60' of the frame of the apparatus by

bolts passing through the lug 70' and the block pieces 66, and is otherwise removed from the face of the plate 60' sufficiently to form a slot in which the rocking arms or feeders 59 move; the space between the curved faces of the two rockers being closed by the projecting rib 69 which is of the same thickness as the rocking arms. These rocking arms 59 are keyed to short shafts 58' by keys 59', the shafts 58' being journaled in journal bearings extending from the plate 60'. In the upper face of the rocking arms 59 are grooves 61 of such shape and size as to hold the nut vertically when the arms are raised; the inner portion of the groove terminating in an abrupt upwardly extending curve, the upper corner of which is rounded to prevent the lodgment of the nuts thereon. At the upper portion of the projecting rib 69 are shoulders 69' which serve as stops to the upward movement of the rocking arms 59. In rear of the pivoted ends of the arms 59 are filling blocks 66 which close the space at this point between the hopper and the face of the plate 60', the purpose being to prevent the escape of the nuts contained in the hopper when the free end of the arm 59 is raised. Pivoted to the plate 60 above the delivery portion of the groove 61 is a swinging arm 71 which is pivoted on a pintle or rod 72, the lower end of the arm extending down into the path of the nuts moving in the groove. When the chute, into which the nuts are delivered, is full so that no more nuts can be delivered therein, the rear end of the swinging arm 71 strikes against the last nut delivered, and is thus prevented from being swung aside to permit the passage of other nuts from crowding into the chute in the wrong position. Leading from the end of the groove 61, adjacent to the pivoted point of the arm 59, is a vertical chute 62 which carries the nuts from the hopper to the matrix in which the nuts are tapped. Keyed to the short shafts 58' are the arms 58, to the outer ends of which are pivoted the toggle lever arms 57, the inner ends of which arms 57 are pivoted or toggled to the vertical rod 56 to which is keyed a collar 55 and on which is a sliding washer 53'. Between the washer 53' and the collar 55 is a coil spring 54. The lower portion of the arm 56 passes through and is guided in its movement by an opening in the bed plate of 120. the apparatus.

Journalized in journals 51 on the bed plate of the apparatus is a longitudinal shaft 50 driven by a belt wheel 49. Keyed to the shaft 50 is a cam 52 on which rests a lever arm 53 which is pivoted to a standard extending from the bed plate. The outer end of this arm 53 is slotted to permit the passage of the rod 56; the portions of the arm on each side of the slot bearing against the 130

sliding washer 53'. By rotation of the shaft 50 the cam 52 is caused to raise and lower the arm 53 which raises and lowers the rod 56, thus operating the toggle arms 57, and through the connecting mechanism the feeding arms 59 which causes the arms 59 to rise in the hopper 60 to the position shown in dotted lines in Fig. 9, a certain number of nuts being engaged and lifted in the groove 61 which, when the arms 59 are in their elevated position, form inclined ways leading into the chutes 62. The purpose of the spring 54 is to impart a yielding movement to the rod 56. Extending from the filling blocks 66 are curved projections 68 which fit over the rounded end of the arm 59 adjacent to its pivotal point and serve to prevent any nuts from collecting between the body of the block 66 and this end of the arm 59. This chute 62 is square in cross section forming passages substantially equal to the area of the nuts; that is, it corresponds to the shape of the nut allowing the nuts to fall to the lower end of the chute without clogging. In the side of the chutes, near the lower ends thereof, are openings 63 through which bolts or pins may be inserted to block or stop the passage of the nuts through the chutes. At the ends of the chutes 62 are sliding plates 46 which normally close the bottom opening of the chutes 62; the plate being held in its closed position by the springs 48 and 48', and extending downwardly from the plate 46 is an arm 46' in the path of a pushing rod 42 which is carried by a sleeve 43 which is supported by the standards 45 and 34', one end of the pushing rod being secured to the hanging arm 41, the upper end of which is provided with a journal which fits loosely on the shaft 8 between the gear wheel 7, and a collar 39 which is keyed to the shaft, whereby the shaft 8 rotates freely in the journal of the arm 41 and yet carries the arm 41 with the reciprocating movement of the shaft, thus causing the rod 42 to press the arm 46' against the force of the springs 48 and 48', moving the plate 46 from beneath the chute 62 with the movement of the bit 12. This allows the nut previously tapped by the bit 12 to drop from the bottom of the chute. It will be noted that the matrix in which the nut is tapped, is formed by the sides of the chute, by a nut which has passed in the chute below the tapping bit 12, and is supported by the plate 46, and by the column of nuts in the chute 62. The operation of my device is as follows:—The blank nuts being fed into the hopper 60, and power applied to the shaft 50 through the band wheel 49, the cams 52 at each end of the apparatus lift the lever arms 53 which operates the vertical rods 56, the toggles 57, 58, and raise and lower the feeding arms 59 which feed the blank nuts into the chutes 62. When the

chutes are filled the swinging arm 71 coming in contact with the uppermost nuts in the chutes prevent any more from entering; the action of the arms 59 thereafter resulting in merely tumbling the blanks in the hopper. When the chutes have thus been supplied with blanks, power is applied to the belts leading to the belt wheel 4 which imparts motion to the central shaft 2 causing the gear wheels 6 and 7 to rotate, thus imparting a rotary movement to the two shafts 8, 8, and, as the shafts rotate in the threaded box 9, they are caused to move forwardly at one end of the apparatus, the tap 12 entering the opening 64 of the matrix 80 tapping the nuts contained therein. As the gear wheel 14 revolves it imparts movement to the gear wheel 15 and threaded shaft 16 which, as the shaft is held from longitudinal movement, imparts motion to the threaded blocks 17, 17, and as the tapping operation is completed one of the blocks 17 comes in contact with the lever arm 18 throwing it over and reversing the movement of the shaft 2 by shifting the belts on the wheels 5 and 4, this being accomplished by means of the lever arms connecting the shaft 19 with the sliding rod 25, and thereupon the taps 12 which have completed their tapping operation are withdrawn while the tapping dies 12 at the other end of the apparatus are moved forward in a like manner as has been described. The rod 42 being connected with the hanger 41 on the shaft 8 moves forward with the shaft and pushes back the sliding plate 46 releasing the nut at the bottom of the matrix 47, allowing it to drop from the chute. When the tap 12 is withdrawn from the matrix the plate 46 having returned to its normal position under the power of the springs 48 and 48' retains the threaded nut released from the tap as it drops to the bottom of the chute where it serves to support the next succeeding blank and holds it in position to be tapped on the return of the tap.

Among the advantages of my invention which may be appreciated by those skilled in the art, is the simplicity of the apparatus which requires a minimum of power and allows positive and rapid operation of the parts, thus enabling the nuts to be tapped rapidly and at small expense.

What I claim and desire to secure by Letters Patent is:—

1. In an automatic nut tapping machine, the combination of a main shaft having reversible driving mechanism, a rotary reciprocating tapping shaft, a rotary reversing shaft having a threaded portion, threaded stop blocks carried by said reversing shaft and adapted to be reciprocated by the rotation thereof, and devices adapted to be operated by the blocks and connected with the reversing mechanism.

2. In an automatic nut tapping machine, the combination of a main shaft having reversible driving mechanism, a rotary reciprocating tapping shaft, a rotary reversing shaft having a threaded portion, threaded stop blocks carried by said reversing shaft and adapted to be reciprocated by the rotation thereof, said blocks being adjustable upon said reversing shaft to regulate the relative position of said blocks thereon, and means for maintaining said blocks in adjustable position, and devices adapted to be operated by the blocks and connected with the reversing mechanism.
3. In an automatic nut tapping machine, the combination of a main shaft having reversible driving mechanism reversing mechanism therefor, a rotary reciprocating tapping shaft, broad and narrow gears in mesh and carried respectively by said shafts, a thread fixed on the tapping shaft and engaging with a fixed threaded bearing, and means controlled by the tapping shaft for automatically actuating said reversing mechanism at each end of its travel.
4. In an automatic tapping machine, the combination of a main shaft having reversible driving mechanism, a rotary reciprocating tapping shaft, a rotary reversing shaft, means connecting the main and the tapping shafts, and means connecting the tapping and the reversing shafts, each means comprising a broad gear on one shaft and a narrow gear on the other shaft in mesh therewith, and reversing mechanism actuated by said broad and narrow gears and connecting the tapping and reversing shafts.
5. In an automatic nut tapping machine, the combination of a rotary reciprocating tapping shaft, a reversing shaft, a thread on the reversing shaft, reciprocating threaded blocks engaging with the thread of the reversing shaft, a rocking lever situated in the path of the blocks, and mechanism connecting the rock lever with the reversing mechanism.
6. In an automatic nut tapping machine, the combination of a main shaft having reversing mechanism, a threaded tapping shaft, a threaded bearing in which the tapping shaft is journaled, a power communicating device fixed to the main shaft, a power communicating device fixed to the tapping shaft adapted to reciprocate therewith and engaging directly with the power communicating device of the main shaft, and mechanism continuously actuated by the tapping shaft for automatically causing an intermittent action of the reversing mechanism and a consequent reversal of the direction of rotation of said shaft at each end of its travel.

In testimony whereof, I have hereunto set my hand.

HUBERT CREHAN.
